COMBINED CUP AND POURING HOSE ATTACHMENT FOR A CAN OR THE LIKE

Frank S. Flider, Chicago, Ill., assignor to The Justrite Manufacturing Company, Chicago, Ill.

Filed Dec. 14, 1970, Ser. No. 26,491

Term of patent 14 years

Int. Cl. D9—07

U.S. Cl. D9—290

FIG. 3

FIG. 4

FIG. 1 is an elevational view of a combined cup and pouring hose attachment for a can or the like showing my new design;

FIG. 2 is an elevational view looking from the right of FIG. 1;

FIG. 3 is a top plan view;

FIG. 4 is a bottom plan view; and

FIG. 5 is an enlarged, fragmentary perspective view showing the upper portion thereof.

I claim:

The ornamental design for a combined cup and pouring hose attachment for a can or the like, as shown.
